UNITED STATES PATENT OFFICE

112,771

DESIGN FOR A LETTER TRAY OR SIMILAR ARTICLE

Francis F. Braun, Cincinnati, Ohio, and Thomas Hearn, Ludlow, Ky., assignors to The Globe-Wernicke Company, Norwood, Ohio, a corporation of Ohio

Application June 3, 1938, Serial No. 77,554

Term of patent 14 years

To all whom it may concern:

Be it known that we, Francis F. Braun and Thomas Hearn, citizens of the United States, residing in Cincinnati, in the county of Hamilton and State of Ohio, and Ludlow, in the county of Kenton and State of Kentucky, respectively, have invented a new, original, and ornamental Design for a Letter Tray or Similar Article, of which the following is a specification, reference being had to the accompanying drawing, forming part thereof.

In the drawing:

Figure 1 is a front elevation of an assembly of two letter trays.

Fig. 2 is a rear elevation of the same.

Fig. 3 is a side elevation of the same.

Fig. 4 is a plan view of the same.

Fig. 5 is a cross sectional view of the same taken on the line 5—5 of Fig. 4.

The salient features of our design include the configuration of the individual trays, the sloping arrangement of the floor of each tray together with the curvature of said floor at the front of the tray, and the configuration and location of the stacking or supporting elements at the rear of the design, so that the space between trays at the front of the complete design may be unobstructed.

We claim:

The ornamental design for a letter tray or similar article, as shown and described.

FRANCIS F. BRAUN.
THOMAS HEARN.
